UNITED STATES PATENT OFFICE.

FREDERICK SOHON, OF WASHINGTON, DISTRICT OF COLUMBIA.

CARBURETER.

1,134,021.

Specification of Letters Patent. Patented Mar. 30, 1915.

Application filed November 14, 1913. Serial No. 800,957.

To all whom it may concern:

Be it known that I, FREDERICK SOHON, a citizen of the United States, residing at Washington, District of Columbia, have invented certain new and useful Improvements in Carbureters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to internal combustion engines but more particularly to a carbureting device therefor, and the invention has for its object to provide a simple and efficient carbureter for internal combustion engines so constructed and arranged that the fuel oil is, upon the suction stroke of the motor, relieved of a portion of atmospheric pressure in such manner that the fuel oil so relieved will be instantly volatilized, 25 thus producing an absolute carburetion of the air passing to the motor.

A further object of the invention is to provide a carbureter in which the fuel is relieved of a portion of the atmospheric pressure to instantly volatilize the same and in which the volatilized fuel is aspirated by the incoming air and drawn therewith into the combustion chamber of the motor to which the carbureter is applied.

35 A further object of the invention is to provide a carbureter in which the fuel oil is relieved of a portion of atmospheric pressure to instantly volatilize the same and in which the proportion of said volatilized fuel and air can be readily adjusted in order to provide the proper proportion of gas and air passing to the motor.

With this and other objects in view the invention consists in the novel construction 45 of the carbureter and particularly in the arrangement of a chamber for the fuel oil so arranged and constructed that upon the passage of atmospheric air through the carbureter the fuel oil in said chamber is relieved of a portion of atmospheric pressure so that the desired amount of said fuel oil is instantly volatilized.

The invention further consists in the construction and arrangement of a carbureter 55 as just defined in which the atmospheric air

passing through the carbureter aspirates the volatilized gas causing it to commingle with the incoming air and to be led to the motor in a thoroughly mixed and gaseous condition.

The invention further consists in certain other novel details of construction and in combinations of parts, all of which will be first fully described and afterward specifically pointed out in the appended claims.

Referring to the accompanying drawing—Figure 1 is a vertical sectional view taken through a carbureter constructed in accordance with this invention. Fig. 2 is a similar view showing a modified embodiment of the carbureter.

Like numerals of reference indicate the same parts throughout the two figures in which;—

1 indicates the carbureter having the usual inlet connection 2, float controlled valve 3, float 4, float chamber 5 and air inlet 6, the design, construction and arrangement of the parts just referred to being immaterial as far as this invention is concerned.

Referring to the construction embodying this invention it will be seen from reference to Fig. 1 that a nipple 7 is arranged centrally of the float chamber, the same having an aperture 8 through which the fuel oil 9 within the float chamber passes to the interior 10 of the said nipple 7. A valve 11 having a threaded stem 12 regulates the flow of fuel oil through the aperture 13 in the top of the nipple 7, said valve controlled by aperture 13 communicating with a transverse passage 14 in the nipple 7, the upper portion 15 of which forms the stem for the mushroom element 16 which will hereinafter be termed a hood. The stem 15 supporting the hood 16 is reduced as shown to provide an annular chamber 17 surrounding the stem 15 for the reception of the fuel oil, which chamber 17 is open at its top and communicates with a volatilizing chamber 18 directly under the hood 16, the top or covering 19 of the float chamber being provided with a vent 20 for the float chamber.

Centrally of the mushroom stem 15 is an opening 21 which receives the stem 22 of the mixture regulating element 23 which will hereinafter be termed the mixture adjusting hood, said mixture adjusting hood 23 being provided with a plurality of openings 24 as is clearly shown in the accompanying draw-

ings, a coil spring 25 being arranged under the stem 22 to maintain said mixture adjusting hood in an elevated position.

As will appear from the accompanying drawings the hood 16 above the volatilizing chamber 18 has its edge depressed at 26 in order to provide a narrow annular opening 27 between the periphery of the hood and the upper surface of the top or cap 19 of the float chamber; while it will be seen that the mixture adjusting hood 23 is provided with a depending flange 28 and an intermediate depressed portion 29 which coincides with the depressed edge 26 of the hood 16.

Arranged above the mixture regulating hood 23 is a cam 30 in engagement therewith, said cam being connected to an arm 31 shown in dotted lines in the drawings by means of which the mixture regulating hood 23 can be raised or lowered in the manner as illustrated in dotted lines in Fig. 2. When the said hood is in its lowermost position the depressed portion 29 thereof engages the depressed edge 26 of the hood 16 and closes communication between the air intake opening 6 of the carbureter and the openings 24 in the mixture regulating hood 23; while when the mixture regulating hood 23 is in its uppermost position all air entering the intake 6 must pass through the openings 24 in the mixture regulating hood 23 as will be perfectly apparent from an inspection of Fig. 2, the said mixture regulating hood 23 being shown in dotted lines in its lowermost position and also shown in dotted lines in its uppermost position. A butterfly valve 32 of usual type is arranged in the carbureter for the usual purposes.

Referring now particularly to Fig. 2 it will be seen that the construction herein described differs slightly from that illustrated in Fig. 1 in that the volatilizing chamber 18 is in direct communication with the float chamber of the carbureter, the said float chamber of the carbureter shown in Fig. 2 not being vented for a purpose which will be hereinafter fully described. Aside from this modification the material features of the device are the same in both constructions.

In order to bring about the result obtained by applicant and particularly the aspiration of gaseous fuel from the volatilizing chamber 18 it is essential that the annular opening 27 while relatively narrow should be sufficiently large to enable egress of the volatilized fuel through the same and into the surrounding air passage in sufficient quantity to produce the proper explosive mixture. By reason of this construction and of the construction of the volatilizing chamber, which is closed to the atmosphere except at the fuel supply opening and at the aspirating opening, a sufficient quantity of vaporized fuel which can be varied at the will of the operator can be drawn out of the vola-

tilizing chamber to be mixed in the surrounding air passage to provide an explosive mixture. A few small perforations would not be sufficient to permit the egress of a sufficient quantity of vaporized fuel to produce a proper explosive mixture, although they would allow a sufficient quantity of liquid fuel to pass therethrough to be vaporized in the surrounding air passage or to be carried into the engine manifold by the incoming air in a liquid condition, as a spray. Therefore, on account of the volume of vapor necessary in a proper explosive mixture and the fractional time in which it must be secured from the carbureter, a decided advance in the art is made by having this vaporizing chamber closed, except as specified, and with an aspirating opening of ample area to pass the required amount of gaseous fuel in a carbureter which is to deliver its fuel in a gaseous form as distinguished from carbureters which deliver it as a spray.

In the action of this carbureter as in all simple carbureters the pressure within the carbureter and in the present instance the pressure in the air passage surrounding the volatilizing chamber is less than atmospheric, the reduction of pressure depending upon the capacity of the surrounding air passage and the piston speed of the motor. By the construction of applicant's volatilizing chamber which is closed to the atmosphere to prevent ingress of air thereto, a pressure is produced in said volatilizing chamber which is lower than the reduced pressure in the surrounding air passage. So long as a pressure is produced in the volatilizing chamber which is lower than the pressure in the surrounding air passage and so long as there are no openings or leaks in the volatilizing chamber communicating with the atmosphere except the openings before noted no liquid can be drawn from a chamber maintained at a lower pressure than the surrounding air passage. In order that fuel in liquid form be drawn out of a chamber it is quite essential that the pressure in the surrounding air passage be not higher than the pressure in the chamber, as liquid will not normally flow against air pressure. In order therefore to obtain a supply of liquid fuel from a chamber into a surrounding air passage it is quite necessary that the chamber be so constructed as to admit atmospheric air for the purpose of relieving the sub pressure or entraining the liquid or it is necessary that the liquid be fed to the chamber by gravity or other pressure, so as to provide and compensate for the reduced pressure within the chamber.

It is applicant's intention to prevent the egress of fuel in liquid form from the volatilizing chamber and to so construct said chamber closed to the atmosphere that the liquid fuel will not be entrained and to

guard against an issue of liquid fuel from the volatilizing chamber. In applicant's arrangement the reduced pressure within the closed volatilizing chamber causes the liquid fuel to be retained and readily volatilized to compensate for the said reduced pressure in the volatilizing chamber, and as said fuel in its volatilized form greatly increases its volume the said fuel in its volatilized form 5 is in turn aspirated out of the aspirating opening into the surrounding air passage, which aspirating opening as before noted must be of sufficient capacity to allow a sufficient volume of volatilized fuel to pass 10 therethrough into the surrounding air passage.

Having thus fully described the several parts of this invention its operation is as follows: The fuel oil being led to the float 15 chamber, the level of which is regulated by the float commanded valve 3, air is drawn in through the air intake 6 and passes upwardly through the carbureter. According to the position of the mixture regulating 20 hood 23 more or less of the air is caused to pass under the mixture regulating hood 23 and to pass through the openings 24 therein. According to the position of the cam 30 and the mixture regulating hood 23 either the 25 entire amount of air can be caused to pass under the mixture regulating hood 23 and through the apertures 24 therein, or when the said hood is in its depressed position the entire amount of air passes on the outside 30 and around the edges of the mixture regulating hood 23 so that no part or portion thereof will pass under the said hood and through the said openings 24 therein. Assuming for the purpose of this specification 35 that the position of the mixture regulating hood 23 is correct for a given mixture, as shown in full lines in the two figures, it will be seen that a portion of the air entering the air intake 6 passes under the mixture regulating hood 23 and through the openings 24 therein, while a portion of the said air passes around the outside of the mixture regulating hood 23 commingling with the air passing through the openings 24 above 40 said openings and the said mixture passing thence to the motor. As the air passes under the mixture regulating hood 23 on its way to the openings 24 therein it rushes at high velocity past the narrow annular opening 27 45 between the aspirating hood 16 and the edge of the cover 19 for the float chamber, the velocity being dependent on the volume of air allowed to pass under the mixture regulating hood 23. This passage of the air 50 past this narrow opening produces an absolute aspirating effect which draws the air from within the chamber 18 thereby lowering the pressure within said chamber and causing the contents therein to be maintained 55 at less than atmospheric pressure according 60

to the velocity of air past the annular opening 27. Volatile fuel oil within the chamber 29 in Fig. 1 and within the float chamber in Fig. 2 being thus relieved of atmospheric pressure will be instantly volatilized in proportion as its surface pressure is relieved and will be aspirated out of the chamber 18 through the narrow annular opening 27 in a perfect gaseous condition. The air then 65 passing by the narrow annular opening 27 picks up the volatilized gas and carries it through the openings 24 in the mixture regulating hood. At the same time the air is passing through said openings 24 a portion of the air entering the carbureter is passing 70 around the outside of the mixture regulating hood 23 and meeting the carbureted air above the openings 24 in the mixture regulating hood 23 the atmospheric air and carbureted air commingle and are thence carried to the motor.

It will be perfectly apparent from an inspection of the accompanying drawings that the quantity of air which passes by the narrow annular opening 27 under the hood 16 75 is controlled by the position of the mixture regulating hood 23 to such an extent that either the entire quantity of air can be caused to pass by the narrow annular opening 26 or all of the air can be caused to pass 80 around and over the mixture regulating hood 23. By means of the cam 30 the mixture regulating hood 23 can be adjusted so as to cause any desired quantity of the air to be carbureted and to be mixed with the 85 atmospheric air passing around the outside of the mixture regulating hood 23. By means of this construction an absolutely perfect mixture of air and gas can be effected.

Referring again to the indicated position 90 of the hood 23 as being correct for a predetermined mixture it will be apparent that as the engine speed increases the velocity of the air through the carbureter past the annular aspirating crack 27 will be increased, thus increasing the degree of 95 vacuum within the volatilizing chamber 18 which increase of vacuum within the volatilizing chamber 18 is not in mathematical ratio with the said increase in air velocity 100 past the aspirating crack or opening 27, consequently the tendency to over feed at high engine speeds is corrected, the needle valve and the aspirating opening being so proportioned to the motor piston displacement 105 as to secure this proper mixture.

It will be understood that the salient feature of this invention is the construction of the device in such manner that the vapor in the volatilizing chamber is drawn out of 110 the chamber by aspiration through the aspirating opening faster than the fuel can replace the vapor so aspirated, thus producing a partial vacuum in the said aspirating chamber which is sustained as long as the 115

motor is in operation to constantly volatilize the fuel in the said volatilizing chamber.

It is quite essential to the proper operation of this device that the volatilizing chamber 18 has no communication with the atmosphere other than at the fuel supply opening and at the aspirating opening so that a reduced pressure can always be maintained within the volatilizing chamber, so as to properly volatilize the fuel within the volatilizing chamber, and not on the outside thereof, as would of course obtain if the liquid fuel were drawn out of the aspirating chamber through fuel openings provided for that purpose. If a chamber be provided for receiving a fuel supply and said chamber is in communication with the atmosphere or atmospheric pressure at points other than the fuel supply opening and aspirating opening, then it will be impossible to maintain a reduced pressure within the said chamber sufficient to thoroughly volatilize the liquid fuel, and consequently no complete volatilizing of the fuel will occur within the same. It is therefore essential to this device that the volatilizing chamber be so constructed and arranged that it is closed to atmospheric pressure at all points other than the fuel supply opening and the aspirating opening, otherwise a draft of air will be set up and maintained within the volatilizing chamber, sufficient to cause liquid fuel to be drawn therewith out of the aspirating opening or openings. While I have shown two embodiments of this invention in the accompanying drawings it is of course apparent to those skilled in the art that certain changes, alterations and modifications can be made without departing from the spirit of this invention as defined by the following claims, as it is only essential to this invention that a chamber be provided in which the fuel oil is relieved of a portion of atmospheric pressure in order to instantly volatilize the same and to provide further means for mixing this vapor with atmospheric air passing into the carbureter.

Having thus fully described the invention what I claim as new and desire to secure by Letters Patent of the United States is:—

1. A carbureter for internal combustion engines, comprising a volatilizing chamber, having an aspirating opening, an air passage in communication with said chamber by means of said aspirating opening to cause an aspirating effect at said aspirating opening to form a partial vacuum within said chamber, said aspirating opening being sufficiently large to permit egress of a sufficient quantity of fuel in volatilized form to pass therethrough into the said air passage to produce an explosive mixture, and means for maintaining a supply of fuel oil in communication with said chamber in such man-

ner that the partial vacuum formed in said chamber will volatilize said fuel oil, said chamber being open to the atmosphere only at the fuel supply opening and at the aspirating opening and means for regulating the extent of partial vacuum in said chamber.

2. A carbureter for internal combustion engines, comprising a volatilizing chamber, having an aspirating opening, an air passage in communication with said chamber by means of said aspirating opening to cause an aspirating effect at said aspirating opening to form a partial vacuum within said chamber, said aspirating opening being sufficiently large to permit egress of a sufficient quantity of fuel in volatilized form to pass therethrough into the said air passage to produce an explosive mixture, and means for maintaining a supply of fuel oil in communication with said chamber in such manner that the partial vacuum formed in said chamber will volatilize said fuel oil, said chamber being open to the atmosphere only at the fuel supply opening and at the aspirating opening, a throttle for regulating the amount of explosive mixture passing from the carbureter and means for regulating the extent of partial vacuum in said chamber irrespective of the throttle and for admitting a supply of atmospheric air to said volatilized fuel to provide an explosive mixture substantially as described.

3. A carbureter for internal combustion engines, comprising a chamber, means for maintaining a supply of fuel oil in communication with said chamber, said chamber being provided with an aspirating opening, means for causing an aspirating action at said opening to produce a partial vacuum within said chamber to volatilize the fuel oil in said chamber, a throttle for regulating the quantity of mixture passing from said carbureter and means for regulating the extent of partial vacuum in said chamber irrespective of the said throttle.

4. A carbureter comprising a chamber having a narrow opening, an air passage in communication with said narrow opening of said chamber through which air passage air is adapted to pass at high velocity to cause an aspirating action at said narrow opening of said chamber to produce a partial vacuum therein, means for maintaining a supply of fuel oil in communication with said chamber in such manner that the said fuel oil is volatilized and aspirated from said chamber through the said narrow opening therein, a mixture regulating hood associated with said chamber and adjustable in relation thereto to regulate the velocity of air in said air passage at said narrow opening of said chamber.

5. A carbureter comprising a chamber having a narrow opening, an air passage in

communication with said narrow opening of said chamber through which air passage air is adapted to pass at high velocity to cause an aspirating action at said narrow opening 5 of said chamber to produce a partial vacuum therein, means for maintaining a supply of fuel oil in communication with said chamber in such manner that the said fuel oil is volatilized and aspirated from said 10 chamber through the said narrow opening therein, means associated with said chamber and adjustable in relation thereto to regulate the velocity of air in said air passage at said narrow opening of said chamber, and for admitting a supply of atmospheric air to mix with the volatilized fuel in said air passage, substantially as described and for the purposes set forth.

6. A carbureter comprising a chamber 20 having a narrow opening, an air passage in communication with said narrow opening of said chamber, through which air passage air is adapted to pass at high velocity to cause an aspirating action at said narrow opening 25 of said chamber to produce a partial vacuum therein, means for maintaining a supply of fuel oil in communication with said chamber in such manner that the said fuel oil is volatilized therein to be aspirated from said 30 chamber through the said opening therein, a throttle for controlling the quantity of air and gas passing from said carbureter, and means associated with said chamber to regulate the velocity of air in said air passage 35 at said narrow opening of said chamber irrespective of the bottle position substantially as described.

7. A carbureter comprising a chamber having a narrow opening, an air passage in 40 communication with said narrow opening of said chamber through which air passage air is adapted to pass at high velocity to cause an aspirating action at said narrow opening of said chamber to produce a partial vacuum 45 therein, means for maintaining a supply of fuel oil in communication with said chamber in such manner that the said fuel is volatilized therein to be aspirated from said chamber through the said opening therein, a 50 throttle for controlling the quantity of air and gas passing from said carbureter, and means associated with said chamber to regulate the velocity of air in said air passage 55 of said narrow opening of said chamber irrespective of the throttle position and for admitting a supply of atmospheric air to mix with the volatilized fuel substantially as described and for the purposes set forth.

8. A carbureter including a casing, a vol-

atilizing chamber fixed in relation to said 60 casing, a fuel oil supply in communication with said volatilizing chamber, an air passage in communication with said chamber, a throttle, means for regulating the extent of partial vacuum in said volatilizing chamber 65 irrespective of the said throttle, said volatilizing chamber having an aspirating opening therein large enough to permit a sufficient quantity of volatilized fuel to pass from said chamber into said air passage to 70 produce a combustible mixture substantially as described.

9. A carbureter including a casing, a volatilizing chamber therein and spaced from said casing to provide an air passage, said 75 chamber being provided with an aspirating opening in communication with said air passage, and means for dividing said air passage to control the quantity and velocity of air at said aspirating opening substantially 80 as described.

10. A carbureter including a casing, a volatilizing chamber therein and spaced from said casing to provide an air passage, said 85 chamber being provided with an aspirating opening in communication with said air passage and means for dividing said air passage to control the quantity and velocity of air at said aspirating opening and for closing off either of the branches of said divided 90 air passage.

11. A carbureter including a casing, a volatilizing chamber therein, a fuel oil supply to said chamber, an air passage, said 95 chamber being provided with an aspirating opening in communication with said air passage, means for dividing said air passage and for regulating the quantity and velocity of air at said aspirating opening to control the extent of partial vacuum within said 100 chamber.

12. A carbureter including a casing, a volatilizing chamber, a fuel oil supply to said chamber, said chamber being provided with an aspirating opening, an air passage in 105 communication with said aspirating opening, a throttle, means for controlling the velocity of air in said air passage at said aspirating opening and for regulating the extent of partial vacuum in said chamber 110 irrespective of the said throttle.

In testimony whereof, I affix my signature, in presence of two witnesses.

FREDERICK SOHON.

Witnesses:
